UNITED STATES PATENT OFFICE

LYMAN C. HUFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS AND APPARATUS FOR CRACKING OIL

Application filed April 14, 1923, Serial No. 632,018. Renewed October 1, 1928.

This invention relates to improvements in a process and apparatus for cracking oil, and refers more particularly to the cracking of petroleum oils to recover therefrom the low boiling point fractions, producing a distillate having the characteristics of gasoline.

Among the important objects of the invention are to provide a process in which one or more perfecting chambers are interposed in the path of the vapors between the carbon separating chamber, and the dephlegmating stage in order to subject the evolved vapors and any condensate separated therefrom, to the action of heat and pressure, thereby increasing the time element for reaction to take place, which results in increasing the capacity of the still. The intermediate vapors or those vapors which normally are returned as reflux condensate from the dephlegmating stage, would be held in the perfecting chambers and subjected to prolonged cracking conditions of heat and pressure, while only the lighter vapors would pass on to the dephlegmator. The condensate from vapors which were condensed in the perfecting chambers could be returned to the heating coil for further treatment. The vapors and any condensate separated therefrom would be held in the perfecting stages at high temperatures and under pressures substantially the same as to which the oil is subjected in the heating tubes. These oil constituents progressing through the perfecting stage would remain therein for a relatively long period of time, and would not be subjected to alternate condensing and evaporating conditions, as is commonly the case with the use of large dephlegmating areas.

Normally, during the dephlegmation of vapors, they are first required to give up a considerable portion of their heat immediately on entering the dephlegmating stage, and are thereafter not subjected to conditions of constant temperature which are known to be most favorable to conversion and cracking.

Further, the fuel consumption of a cracking still using perfecting or consummating chambers, such as described, will be materially reduced, for only the condensate and reflux from the vapors which had not re-

acted, would be returned to the heating tubes to be again subjected to the cracking conditions therein.

Operating the process in a manner described, would eliminate the necessity of re-heating a large quantity of reflux, the vapors of which had been prematurely condensed in the dephlegmator, and not given sufficient time for complete conversion.

On account of the longer time element possible by using the perfecting or consummating chambers, it is unnecessary to heat the oil to such extremely high temperatures in the heating coil, and lower temperatures can be carried in the transfer line, thus subjecting the oil while in the heating tube to conditions more favorable to conversion conditions which promote reaction when discharged into the expansion chambers.

The use of perfecting chambers is a means for converting a larger percentage of oil into fractions having the characteristics of gasoline, and provides a method of attacking and breaking up the intermediate fractions, thus giving a larger degree of conversion and a distillate yield which has a considerable greater uniformity than is normally produced by the use of a single expansion chamber.

The single figure is a diagrammatic side elevational view of the apparatus.

Referring to the drawing, the raw oil or charging stock to be treated is introduced from any convenient source through the pipe 1 and is charged into the top of a dephlegmator 2 where it is utilized as a refluxing medium flowing in an opposed direction to the heated oil vapors rising therethrough. The charging stock with what reflux condensate it collects in the refluxing tower, will flow down through the column, and may be drawn off from the bottom of the reflux leg 3 through the line 4 in which is interposed a valve 5. This line communicates with the suction side of a hot oil pump 6 which charges the oil to the heating coil 7 mounted in the furnace 8, the latter being preferably heated by means of gas burners 9. A by-pass 10 controlled by a valve 11 is connected

around the pump in case it is desired to eliminate the pump from the system.

In the heating coil, the oil is raised to a conversion temperature, while a substantial pressure is maintained thereon. In this condition, it is directed through the transfer line 12 regulated by a valve 13, and is introduced into the vaporizing or separating chamber 14. Here the oil is collected in a substantial body, the vapors passing off through the vapor line 15 regulated by a valve 16, to a perfecting chamber 17, while the residual products may be drawn off either continuously or intermittently through the residuum lines 18 controlled by the valves 19.

The chambers 14 and 17 have upper and lower removable heads which facilitate cleaning. The chambers are heavily insulated to minimize the loss of heat by radiation.

The vapors introduced to the perfecting chambers collect therein and assume a partial stagnation, that is their travel due to the character of the chamber, is materially retarded, and due to the high temperature and pressure conditions maintained upon this stage, they have sufficient time to permit the consummation of the cracking reaction initiated in the chamber 14.

It will be noted that in place of one chamber, a series of similar chambers may be connected into the system, whereby considerable greater quantities of hydrocarbon vapors are subjected to this perfecting or consummating action.

In these perfecting stages there will result a condensate which when collected in the bottom of the chamber may be drawn off through pipes such as that shown at 20, regulated by valve 21 and returned to the pipe 4 which connects to the suction side of the recirculating pump 6.

The vapors after having been maintained for a period of time under the cracking conditions of temperature and pressure maintained in the perfecting stage, pass off through the vapor line 22 in which is interposed a valve 23. These vapors are introduced into the lower part of the dephlegmator where they rise and are refluxed by the cooling action of the raw oil with which they come into intimate contact. After being dephlegmated, the vapors pass off through a pipe 24 and are subjected to a final condensing action in the coil 25, after which they are collected as liquid distillate in the receiver 26.

This receiver is equipped with liquid level gauge 27, a pressure relief valve 28, pressure gauge 29, and a liquid drawoff line 30 controlled by a valve 31. The pressure upon the system may be maintained by regulation of the pressure relief valve on the receiver when it is desired to maintain a relatively constant pressure throughout the system, or

differential pressures may be maintained upon the separate stages by manipulation of the valves in the several connecting lines.

By treating a mid-continent gas oil of approximately 32° Baumé gravity to temperatures ranging from 600° to 900° F., and pressures ranging from 50 to 500 pounds, a normal yield of 60% pressure distillate may be obtained from which 55% of Navy specification gasoline may be extracted.

By utilizing the perfecting chambers from a 60% yield of pressure distillate may be separated from 75% to 80% of oil having the characteristics of gasoline. Thus it is obvious that there is a substantially greater splitting up of the hydrocarbon constituents where the vapors are maintained for a considerable period of time under pressure and temperature conditions of cracking subsequent to their vaporization. Obviously, the vapors are more completely broken down and cracked into a distillate predominating in the lighter ends or fractions.

I claim as my invention:

1. A process for cracking oil, consisting in heating the oil to a conversion temperature in a heating zone, in discharging the heated oil into an enlarged conversion zone wherein a substantial body of liquid oil is maintained, in withdrawing the residual products from said conversion zone to be isolated from the system, in directing the evolved vapors through an enlarged chamber wherein they are maintained at substantially the temperature and pressure conditions of the conversion zone, in passing the vapors from said enlarged chamber to a dephlegmator, in condensing the dephlegmated vapors, in collecting the resulting distillate, in returning the condensate collected in said enlarged chamber and the reflux condensate from the dephlegmator to the heating zone for retreatment and in maintaining a regulated pressure on the oil undergoing conversion.

2. A process of cracking hydrocarbon oil, consisting in passing the oil through a heating coil located in a furnace wherein the oil is subjected to a conversion temperature, in discharging the heated oil into an enlarged conversion zone, in maintaining a substantial body of liquid oil therein, in continuously withdrawing residual oil from said conversion zone to be isolated from the system, in passing the evolved vapors to an enlarged chamber maintained at substantially the conditions of temperature and pressure maintained in said conversion zone wherein the vapors undergo additional reaction and portions thereof are condensed, in withdrawing said condensed portions and returning them to the heating zone for retreatment, in passing the still vaporized portions from said enlarged chamber to a dephlegmator, in introducing raw oil into said dephlegmator to act as a dephlegmating medium for said va-

5
pors, in condensing the dephlegmated vapors in collecting the resulting distillate, in passing the raw oil and reflux condensate from said dephlegmator under an applied pressure to and through said heating coil and in maintaining a superatmospheric vapor pressure on the oil undergoing conversion.

3. An apparatus for treating hydrocarbon oil, consisting of a coil located in a furnace, 10 a transfer line connecting said coil with an enlarged conversion zone, means for withdrawing residual oil from said conversion zone, means for passing vapors from said conversion zone to an enlarged insulated 15 chamber, means for withdrawing liquid condensate from said chamber and means for returning such liquid condensate free from residual oil removed from said conversion zone to said coil, means for dephlegmating the vapors issuing from said enlarged chamber, 20 means for condensing and collecting the dephlegmated vapors, means for introducing charging oil to said dephlegmating means, and means for passing reflux condensate together with the charging oil from the dephlegmating means directly to the heating coil without previously admitting the same 25 to said chamber or to said conversion zone.
